UNITED STATES PATENT OFFICE

2,175,783

METAL-ROLLING MILL

George H. Rose, Cleveland Heights, Ohio

Application October 17, 1936, Serial No. 106,235

10 Claims.

(CL. 80—56)

This invention relates to metal-rolling mills and more particularly to adjusting devices therefor.

In the usual two-high rolling mill, one or both 5 of the rolls are vertically adjustable by means of screws and wedges. A longitudinal or axial adjustment is effected by clamps or other elements which press the chocks at each end of the roll against the shoulders formed at each end of 10 the barrel of the roll. This method of adjustment results in wear on the chocks and rolls, which permits the rolls to move axially with respect to each other; consequently the section being rolled varies in its dimensions.

15 In addition to the foregoing difficulties, further variations in the dimensions of the section being rolled are caused by horizontal clearance between the chocks and rolls. This clearance is necessary to permit the installation and removal 20 of the chocks from the housing, but permits the movement of the chocks especially when the section being rolled enters or leaves the rolls.

It is among the objects of the present invention to provide a novel adjusting device for the 25 rolls of a rolling mill which will enable their exact registration under all conditions.

The foregoing and other objects will be apparent after referring to the drawings, in which:

Figure 1 is a sectional plan of a rolling mill 30 employing the device of the present invention.

Figure 2 is a view on the line II—II of Figure 1.

Figure 3 is an end elevation.

Figure 4 is a sectional plan similar to Figure 1 35 but disclosing a modification.

Figure 5 is a perspective view of a modified form of the invention.

Referring more particularly to the drawings, the numeral 2 designates a rolling mill housing 40 having the usual windows 3. A pair of chocks 4 are disposed in the lower portions of the windows 3 and carry a roll 5 which is journaled therein. A similar pair of chocks 6 are disposed in the upper portion of the windows 3 and carry 45 a roll 7 which is journaled therein. The lower chocks 4 rest on the bottoms of the windows 3 of the housing 2, while the upper chocks 6 are adjusted vertically with respect thereto by means of the usual screwdown 8.

50 The bearings 9 in the chocks 4 and 6 may be of any desired type and can be held in place by closure plates 10 and bolts 12.

Each of the closure plates 10 carries a pair of outwardly extending wings, or ribs, 14 which are spaced substantially parallel to the roll axis.

These wings, or ribs, 14 extend substantially on both sides from the common vertical center line of the rolls 5 and 7.

The mill housing 2 carries a vertical pin 15 adjacent each of the chocks (4 and 6) of the mill. 5 Each pin 15 carries an inner link 16 which extends across the closure plate 10 of the adjacent chock, and an outer link 17 which embraces the link 16 in spaced relationship.

Each pair of outwardly extending wings, or 10 ribs, 14 on each of the closure plates 10 carries a pin 18 to which there is connected a clevis 19. Each lever 16 is connected to the adjacent clevis 19 by a pin 21.

Each pair of outwardly extending wings, or 15 ribs, 14 also carries a pin 23 to which there is connected a clevis 24. Each lever 17 is connected to the adjacent clevis 24 by a pin 25.

On the face of the housing 2 opposite each of the vertical pins 15 there is mounted a vertical 20 pin 26. Each vertical pin 26 carries an outwardly extending eye-bolt 27 on the outer end of which there is threaded a nut 29. The extended end of each lever 16 is right-angularly grooved, as at 30, to embrace the adjacent eye-bolt on the inner side of the nut 29. On the face of the housing 2 beside each of the vertical pins 26 there is mounted a vertical pin 32. Each vertical pin 32 carries an outwardly extending eye-bolt 33 on the outer end of which there is threaded a nut 34. 30 The extended end of each lever 17 is right-angularly grooved, as at 35, to embrace the adjacent eye-bolt 33 on the outer side of the nut 34.

From the foregoing it will readily be seen that the adjustment of the nuts 29 and 34 toward and 35 away from the mill housing 2 effects a similar adjustment of the levers 16 and 17. Accordingly the chocks 4 and 6 and rolls 5 and 7 are adjusted axially with respect to each other. This enables the exact alinement of the grooves X of the rolls. 40

In order to prevent the horizontal displacement of the chocks 4 and 6 and consequently the rolls 5 and 7 in the housing 2, the following construction is provided:

Both sides of each window 3 carries a liner 36. 45 One side of each window 3 is provided with a transverse and tapered keyway 37. Each keyway 37 has disposed therein a wedge-shaped key 38 which carries a right-angular extension 39. The right-angular extension 39 on each of the wedge-shaped keys 38 is bored to receive the threaded end of a bolt 41 which is suitably secured to an adjacent portion of the housing 2. The threaded end of each bolt 41 carries a pair of nuts 42, one 50 on each side of the right-angular extension on

each of the wedge-shaped keys 38. By proper manipulation of the nuts 42 the wedge-shaped keys 38 may be moved to keep the chocks 4 and 6 snugly occupying the windows 3 in the housing 5 2, whereby horizontal displacement is avoided.

Referring to Figures 2 and 4, it will be noted that the apertures in the links 16 and 17 and the clevises 19 and 24 are made decidedly larger than the diameters of the pins 21, 25, 18 and 23, respectively; likewise, the pins 15, 15', 26 and 32 are 10 preferably substantially smaller than the clevis and arm apertures through which they pass in mounting the arms and associated members to the housing. In each case the inner faces of the 15 apertures are annularly convex to provide a curved bearing, constricted adjacent its central portion and flared outwardly to each side thereof. This construction, which permits of relative vertical movements being effected between the several 20 parts without binding or jamming, is clearly shown in Figures 2 and 5. It will be seen that unless the nuts 29 and 34 are set to the greatest degree in opposition, the parts will be loosely joined together and capable of being ineffectually 25 shifted or jostled by the lost motion relationship afforded by the oversized pin receiving apertures.

It will also be observed that when the nuts 29 and 34 are set in opposite directions to the practical limits, the various pins are drawn into forceful bearing engagement upon a side wall of their 30 respective apertures, and the opposing forces thus set up tension all the elements to the end that each is rigidly and immovably fixed relative to the others. Hence, the roll chocks, being integrally affixed to certain of the elements, are 35 positively held against horizontal movement axially of the rolls, unless and until an adjustment is effected by resetting the nuts 29 and 34. It is of great importance that a wide range of axial 40 adjustment is afforded by my invention while, at the same time, affording exactness and precision in positioning the rolls relative to each other, and that these desirable results are obtainable without any reliance being placed upon the accurate 45 size and association of the interfitting parts as is usually the case. In fact, by making the pins substantially undersize, the inaccuracies of the pivotal bearings are so amplified as to become of large, definite values, susceptible of being accurately 50 controlled, rather than the ordinarily vague, indefinite values of a magnitude commensurate with the infinitesimal imperfections from which they arise. Thus, the evil is intentionally magnified and positively controlled by 55 setting and resetting the nuts 29 and 34, whereby the utmost in precision of adjustment is had independently of the size of any pin or other elementary part.

Referring to Figure 4 of the drawings, I have 60 disclosed the bearings 9 as being augmented by radial antifriction bearings 45 and 46. The bearing 45 is disposed around the neck of the roll 7 between the end of its barrel and the adjacent side of the chock 6. The bearing 46 is disposed 65 around the neck of the roll 7 and between the outer end of the bearing 9 and a clamping ring 47 which is screw-threaded on the extremity of the roll-neck.

While I have shown and described several specific embodiments of my invention, it will be understood that I do not wish to be limited exactly thereto, since various modifications may be made without departing from the scope of my invention, as defined by the following claims.

I claim:

1. In a rolling mill, a housing, means carried by said housing for mounting a plurality of rolls, said means including a chock, a roll having one of its necks journaled in said chock, means for precluding axial movement between said roll and said chock, adjusting means associated with said housing to move said chock for varying the axial disposition of said roll, said means comprising a plurality of levers having lost-motion connection with said housing and said chock including means 5 for placing said levers in opposition to overcome said lost motion and thereby to rigidly affix said chock relative to said housing, the connection between said levers and said chock being constructed and arranged to afford relative universal 15 movement therebetween.

2. In a rolling mill, a housing, a chock for journaling one end of a roll carried by said housing, a roll journaled therein and secured against axial movement relative thereto, a pair of levers 20 extending across said chock and pivoted upon said housing, each of said levers having pivotal engagement therewith at its point of crossing, and means for positively moving one of said levers away from said housing to pull said chock in one 25 direction and for moving the other of said levers toward said housing to push said chock in the opposite direction.

3. A device for effecting the axial adjustment of rolls comprising a roll journal, a roll rotatably 30 carried therein and secured against relative axial movement thereto, means for moving said roll axially by effecting the movement of said journal comprising a pair of levers each having lost-motion connection with said journal, and means 35 for actuating each of said levers in direct opposition, whereby said lost-motion is taken up and said journal is adjustably anchored by the equilibrium of said opposed levers.

4. In a rolling mill, a device for effecting the 40 axial adjustment of rolls comprising means for gripping the neck of a roll, a lever connected to said gripping means constructed and arranged to move the roll in the direction of its axis, another lever mounted independently of the first 45 named lever constructed and arranged to move said roll in the opposite direction of its axis, and means for actuating said levers in coordination to move said roll axially in either direction and for actuating said levers in opposition to securely 50 anchor said roll.

5. In a rolling mill, a housing, a chock for journaling one end of a roll carried by said housing, a roll journaled therein and secured against axial movement relative thereto, a pair of levers 55 pivoted upon said housing, each of said levers extending from its point of pivot on said housing across said chock to a point of adjustment with the housing on the opposite side of said chock; means for each lever at said point of adjustment 60 to control its position about its pivot relative to the housing, and means for connecting each of said levers to said chock at the point where it crosses the latter.

6. In a rolling mill, a housing, a chock, an axial 65 extension on said chock, a pair of levers pivoted upon the housing, said levers extending across said chock in cooperative relation to said axial extension, means for connecting said levers independently to said axial extension, and means 70 for moving said levers coordinately to move the chock and for moving said levers oppositely to anchor the same.

7. In a rolling mill, a housing, means for journaling a roll therein, a pair of levers extending

across said housing to overlie said journal-means, a bearing extension affixed to said journal-means so as to extend therefrom crosswise to said levers, and a separate link pivotally connecting each lever to said bearing extension.

5. In a rolling mill, a housing, means for journaling a roll therein, a pair of levers extending across said housing and pivoted to the latter on separate bearings, a bearing extension affixed to 10 said journal-means so as to extend therefrom crosswise to said levers, and a separate link pivotally connecting each lever to said bearing extension.

10. In a rolling mill, a housing, means for journaling a roll therein, a pair of levers extending across said housing to overlie said journal-means, said levers being pivoted to the housing on separate bearings for oscillatory movement in a common plane, a bearing extension affixed to said

journal-means so as to extend therefrom crosswise to said levers, and a separate link pivotally connecting each of said levers to said bearing extension.

15. In a rolling mill, a housing, a pair of pivot bearings carried by the housing, a lever mounted for oscillation in each of said bearings, a roll chock disposed in said housing, a clevis bearing extending axially from the chock, each of said levers extending across said housing in the plane 10 of said clevis bearing, one of said levers lying within said clevis bearing, a link pivoted to each of said levers intermediate its ends, a pin pivotally securing each of said links to said clevis bearing, and adjustment means associated with 15 each of said levers for varying its position with respect to the housing and with respect to the other lever thereof.

GEORGE H. ROSE.
